Primary Examiner — Samantha Wood

(57) **CLAIM**

The ornamental design for a watch as shown and described.

DESCRIPTION

The patent or application file contains at least one drawing executed in color. Copies of this patent or patent application publication with color drawing(s) will be provided by the Office upon request and payment of the necessary fee.

1.1 is a perspective front, bottom, right side perspective view of a watch showing the new design;

1.2 is a front view thereof;

1.3 is a rear view thereof;

1.4 is a top view thereof;

1.5 is a bottom view thereof;

1.6 is a left side view thereof; and

1.7 is a right side view thereof.

The portions of the watch shown in light pink form no part of the claimed design and are provided for illustrative purposes only.

1 Claim, 7 Drawing Sheets
(4 of 7 Drawing Sheet(s) Filed in Color)
